UNITED STATES PATENT OFFICE.

ROBERT H. EMERY, OF BRIGHTON, IOWA.

CAN-OPENER.

1,223,485.

Specification of Letters Patent. Patented Apr. 24, 1917.

Application filed April 17, 1916. Serial No. 91,720.

To all whom it may concern:

Be it known that I, ROBERT H. EMERY, a citizen of the United States of America, residing at Brighton, in the county of Washington and State of Iowa, have invented certain new and useful Improvements in Can-Openers, of which the following is a specification, reference being had therein to the accompanying drawing.

10 This invention relates to can openers and has for its principal object the production of a simple and efficient means whereby the can top may be removed by one stroke of the can opener.

15 Another object of this invention is the production of a can opener which is so constructed as to efficiently cut a can top from the can, while a plunger is employed for removing the can top which may be carried by

20 the can opener.

A still further object of this invention is the production of a can opener which may be easily operated for allowing the same to be used for removing a can top without possibility of cutting or injuring the hands.

With these and other objects in view this invention consists of certain novel combinations, constructions, and arrangements of parts as will be hereinafter fully described and claimed.

In the accompanying drawings:

Figure 1 is a side elevation of the can opener as constructed in accordance with this invention.

35 Fig. 2 is a bottom plan view of the assembled can opener.

Fig. 3 is a fragmentary vertical section through the central portions of the can opener, portions of the device being shown 40 in elevation.

Fig. 4 is a detail perspective view of one of the cutting blades.

Fig. 5 is a plan view of a certain retaining plate used in connection with this invention.

45 Fig. 6 is a fragmentary elevation of a portion of the device, partly broken away, illustrating how the blades are retained in position.

50 Fig. 7 is a fragmentary plan view of a portion of the device, illustrating how the ears of the blades fit within the notches of the retaining plate.

Referring to the accompanying drawings by numerals it will be seen that the can opener comprises a body 1 having the handles 2 extending from its side portions in substantial

alignment with each other, as shown in Figs. 1 and 2. The body 1 is provided with an overhanging flange 3 and with a number of spaced lips 4 formed in the same plane as the flange 3. This body 1 is further provided with a central opening 5 for purposes to be hereinafter set forth. The can opener employs a pair of blades 6 which are semi-cylindrical in shape while their straight upper edges 7 fit upon the body 1 adjacent the inner portions of the flanges 3. These blades 6 taper to pointed lower ends which constitute cutting portions for the insertion of the blades 6 into the can body. Each blade 70 6 is further provided with a plurality of inwardly bent ears 9 which fit adjacent each other when the two blades are used in connection with the can opener, as shown clearly in Figs. 6 and 7. The retaining plate 10, as 75 shown clearly in Fig. 5, is provided with a number of notches 11 within which the ears 9 are adapted to fit when the can opener is assembled and is in condition to be used.

As the can opener is constructed only two 80 of the notches will be used at a time, although any number of notches may be provided for allowing the convenient assembling of the can opener and for producing a lighter structure in connection with the 85 openings 12 formed in the plate. A hollow neck 13 extends from the central portions of the plate 10 and passes through the opening 5 formed in the body 1. When the can opener is assembled it will be seen that the 90 blades 6 will be held upon the body 1 by means of the ears 9 fitting within the notches 11 formed in the plate 10. After the neck 13 has been passed through the opening 5 of the body 1 it is welded so as to be flared at 95 its upper end as shown at 14, thereby holding the plate against accidental displacement. A headed plunger 15 passes through the neck 13 and carries the washer 16 upon its lower end. It will be seen that after the can opener has been assembled the blades 6 will be positively retained upon the body 1 by fitting within the flange 3 of the body 1, while the depending ears 17 of the plate 10 will be directed positively in alignment with 105 the ears lips 4 of the body 1, as clearly shown in Fig. 2, so as to provide a broad bearing surface for preventing the blades from wobbling or becoming loose when in use. As the plate will be positively retained 110 upon the body 1 by means of the neck 13 it will be seen that the blades will also be re-

tained in their correct positions since the ears 9 thereof will fit within the notches 11 of the plate 10.

When the can opener is in use the points 5 of the blades 6 are positioned upon the top of the can as indicated in dotted lines in Fig. 1. The operator at this time is gripping the handles 2 very firmly so that upon a downward thrust of the can opener the points will pass through the top of the can, while the edges of the blades will cut the top. As the downward movement is continued the top of the can will be evenly cut until it is finally removed from engagement 10 with the can, since the two semi-cylindrical blades 6 will form a complete circle for efficiently removing the can top from the can. After the can is opened the can top will of course, be carried in the upper portions of 15 the blades. Then by exerting a downward pressure upon the headed plunger 15 it will be seen that the can top will be very quickly and efficiently ejected from the interior of the blades. In order to open comparatively 20 flat cans a number of thrusts may be necessary. Under such conditions it will be seen that the top of the can may be easily removed without the necessity of employing the headed plunger.

30 From the foregoing description it will be seen that a very simple and efficient can opener has been produced wherein after the assembling thereof it may be operated for positively removing can tops without danger of injuring the operator's hands, while simple and efficient means is provided for removing the can tops from engagement with the device which removed the same.

What is claimed is:

40 1. A can opener of the class described comprising a body having a flange formed upon its outer portions, blades carried upon said body having tapering edges merging in pointed portions, said blades being provided with inwardly bent ears, a plate positioned upon said body, said plate being provided with notches, said notches being adapted to receive said ears whereby said blades will be retained upon said body, said pointed portions being adapted to be forced through a can cover so as to allow the side edges to cut the can cover from the body thereof.

55 2. A can opener of the class described comprising a body having a flange formed upon its outer periphery, said body further being provided with depending lips formed upon said flange at spaced intervals apart, blades positioned upon said body and engaging the inner portions of said flange and 60 lips, said blades provided with cutting edges and pointed ends, a plate positioned upon said body, said plate provided with a number of spaced depending lips, said lips of said plate being adapted to be positioned in alinement with the lips of said body, where-

by said blades may be clamped in position upon said body.

3. A can opener of the class described comprising a body having a flange upon its outer periphery, blades having tapering 70 edges terminating in pointed ends positioned upon said body and engaging the inner portions of said flange, a plate positioned upon said body, said plate provided with a hollow neck extending through said body, said 75 blades provided with inwardly extending ears, said plate provided with a number of notches, said ears fitting within said notches, whereby said plate will hold said blades upon said body, said neck being flared at its 80 upper end so as to permanently retain said plate upon said body.

4. A can opener of the class described comprising a body having a flange upon its outer periphery, blades having tapering 85 edges terminating in pointed ends positioned upon said body and engaging the inner portions of said flange, a plate positioned upon said body, said plate provided with a hollow neck extending through said body, said 90 blades provided with inwardly extending ears, said plate being provided with a number of notches, said ears fitting within said notches, whereby said plate will hold said blades upon said body, said neck being flared 95 at its upper end so as to permanently retain said plate upon said body, said pointed ends being adapted to be passed through the top of a can so as to allow said edges to cut the can top, whereby the can top may be removed from the can body, at which time the can top will be carried by said blades, and means for facilitating the removal of the can top from said blades.

5. A can opener of the class described, 105 comprising a body having a flange upon its outer periphery, blades having tapering edges terminating in pointed ends positioned upon said body and engaging the inner portions of said flange, a plate positioned upon 110 said body, said plate provided with a hollow neck extending through said body, said blades provided with inwardly extending ears, said plate being provided with a number of notches, said ears fitting within said 115 notches, whereby said plate will hold said blades upon said body, said neck being flared at its upper end so as to permanently retain said plate upon said body, said pointed ends being adapted to be passed through the top 120 of a can so as to allow said edges to cut the can top, whereby the can top may be removed from the can body, a headed plunger passing through said neck, and a washer carried upon the lower end of said plunger, 125 said plunger being adapted to be pressed downwardly so as to cause the lower end thereof and said washer to engage the can top carried upon said blades for facilitating the removal of the can top from said blades. 130

6. A can opener of the class described, comprising a body having a flange, blades positioned upon said body and fitting within said flange, said body having a central opening, a plate positioned upon said body and wedging within said blades, thereby holding said blades upon said body, a neck positioned upon said plate and extending through said opening, said neck being flared at its outer end for fixedly holding said plate upon said body.

7. A can opener of the class described, comprising a body having a flange upon its outer periphery, blades having tapering edges terminating in pointed ends positioned upon said body and engaging the inner portions of said flange, a plate positioned upon said body, said plate provided with a hollow neck extending through said body, said blades provided with inwardly extending ears, said plate being provided with a number of notches, said ears fitting within said notches, whereby said plate will hold said blade upon said body, said neck being flared at its upper end so as to permanently retain said plate upon said body, said pointed ends being adapted to be passed through the top of a can so as to allow said edges to cut the can top, whereby the can top may be removed from the can body, at which time the can top will be carried by said blades.

8. The can opener of the class described, comprising a body having a flange, blades positioned upon said body and fitting within said flange, said body having a central opening, a plate positioned upon said body and wedging within said blades, thereby holding said blades upon said body, a neck positioned upon said plate and extending through said opening, said neck being flared at its outer end for fixedly holding said plate upon said body, said neck having an opening extending therethrough, and a slidable plunger passing through said neck for facilitating the removal of a can top from said blades.

9. A can opener of the class described, comprising a body having a flange, blades positioned upon said body and fitting within said flange, said body having a central opening, a plate positioned upon said body and wedging within said blades, thereby holding said blades upon said body, a neck positioned upon said plate and extending through said opening, said neck being flared at its outer end for fixedly holding said plate upon said body, and means for facilitating the removal of a can top from said blades.

In testimony whereof I hereunto affix my signature.

ROBERT H. EMERY.
